PIPE ORGAN

George M. Quave, West Asheville, N. C.

Application February 7, 1936, Serial No. 62,858

12 Claims. (Cl. 84—335)

This invention relates to pipe organs and more particularly to means for improving the tremolo effects therein.

The tremulant or tremolo is connected by a conduit to the bellows. By its action of rhythmically and abruptly interrupting the escape of a large stream of air, the tremolo causes the lid of the bellows to oscillate up and down, and thus produces a wavering or trembling quality in the music being played. The bellows lid should swing in time with the beat of the tremolo, therefore the lid should swing like the pendulum of a clock, freely and uninterrupted to the end of its natural excursion on both sides of any given or varying center. If the bellows lid is interrupted in any of its excursions, it is thrown out of step with the tremolo, and will presently "cross over" its time, and skip a beat, thus destroying the beautiful effect of the music and tending to stop the tremolo.

The valves previously employed to regulate the flow of air into the bellows have been open to the objection that they did not have a free and even movement at immediately below and immediately above their closing points, and thus seriously interfered with the action of the tremolo when the organist was playing soft music.

The old curtain valve, while it had no fixed closing point, still did not work perfectly with the tremolo, for the curtain valve had no positive action, but depended on gravity for its downward movement. The variations in the amount of air rushing under and against the roller caused a variation in the movement of the roller. The action wasn't quick enough to keep the strings taut, and they would often jump from their pulleys, or cause a swinging motion of the yoke which would affect the free action of the valve. The binding of the cords where they were wound in the grooves at the ends of the roller, and the frequent rubbing of the cords against the holes through which they pass, caused an unevenness in the action of this valve, and prevented its synchronous action with the tremolo.

The pivoted disk valve used in the conduit from the blower, is opened by a chain over a pulley, and closed with a weight. It has a rigid closing point.

The hinged flap or door valve, and the cone valve, while having a positive action, being operated by means of a rod from the bellows lid, have the defect of a fixed and rigid seat at their closing point. When playing the organ on a dry day, when the joints in the organ have shrunk and a quantity of air is escaping, these valves

stay at a considerable distance from their seat, and the tremolo may be used satisfactorily with soft music. But on damp days, when the organ is tight, if soft music requiring a very small quantity of air is played, the valve remains near its seat. Should the tremolo now be turned on, the bellows lid will begin to oscillate up and down. These upward excursions of the bellows lid are often interrupted by the striking of the valve against its rigid seat. This, as explained above, interferes with the action of the tremolo.

An object of the present invention is to provide bellows valves which allow an even and free oscillation of the bellows lid when the tremolo is used.

Another object of the invention is to provide an organ bellows with a non-stop type of valve which will not interfere with the action of the bellows lid when the tremolo is used.

A further object is to provide an improved type of valve for organ bellows which will be silent and free acting under all conditions of use.

These and other objects and advantages of the invention will be apparent from the following specification when taken with the accompanying drawing, in which:

Fig. 1 is a fragmentary side view, with parts in section, of an organ which includes a tremolo, a bellows and bellows valve embodying the present invention;

Fig. 2 is a fragmentary plan view of the lower wall of the bellows and the valve mounted thereon;

Fig. 3 is a fragmentary perspective view of the bellows valve;

Fig. 4 is a sectional view of an organ bellows and another type of the same valve;

Fig. 5 is a plan view of the sleeve of the valve shown in Fig. 4;

Fig. 6 is a perspective view of the sleeve of the valve shown in Fig. 4; and

Fig. 7 is a fragmentary sectional view of a modification which omits a separate air box.

In the drawing, the reference numeral 1 identifies a plurality of pipes which are stepped into the beam and slide assembly 2. The air supply to the pipes is through the wind box 3 and trunk 4, and this supply is controlled by keys 5 or pedals, not shown, in the usual manner.

The trunk 4 opens into the bellows which may be a box or compartment having a lower wall 6 and rigid side walls 7 which are joined to the lid 8 by a flexible bellows section 9. The bellows is seated upon the air box 10 which receives air 55

under pressure from a blower, not shown, through conduit 11.

From the bellows opens another conduit 12 which carries the air supply to the tremolo. 5 When this supply is admitted to the tremolo by a slide 13 it passes into wind box 14 through valve 15 into a compartment of the tremolo having a flexible wall 16, and escapes through a vent 17 of the weighted lid 18. The parts so far 10 described may be of any conventional or desired design as the exact construction is not a material part of this invention.

The bottom wall 6 of the bellows has a large opening 19 in alignment with a smaller opening 15 ing or valve port 19' in the upper wall of the intake box. As shown in the perspective view, Fig. 3, the port opening 19' is of rectangular form and the valve 20 is a rectangular block of wood, with slightly rounded edges, which has a slight 20 clearance, say about 1/64 inch, around it through which a small quantity of air passes in the closed position of the valve. This is offset by the leakage through the organ, and allows the valve to move freely. In a bellows having a top wall 25 three feet square, the valve 20 may be, for example, a wooden block about 4 inches wide, 8 inches long and 2 inches thick. The metal rod 21 extends centrally through the valve and is pivoted in a bore which extends through the 30 upper wall of the inlet box 10, the ends of this bore being sealed by plugs 22. The valve may, of course, be pivotally mounted in other ways, for example, in a board 100 secured to the underside of the bellows, and other arrangements for 35 supplying air to the bellows, such as the supply conduit 101, Fig. 7, may be used. A wood block 23 is fixed to one end of the valve 20 and is bored to receive one bent end of a metal rod 24. The opposite bent end of rod 24 extends through a 40 similar wood block 25 that is fixed to a plate 26 that is fixed over an aperture into the top wall 8 of the bellows by any convenient means, not shown, such as screws or cement. The purpose of the aperture in the bellows lid 8 is to allow 45 an entrance for assembling the valve. The rod is fitted with washers at blocks 23 and 25, and is held in place by cotter pins. The wooden parts that form bearings for the operating rod 24 and the pivot rod 21, also the edges of the valve 20 50 are lubricated, preferably graphited, to reduce friction and prevent noisy operation.

Another form of this valve which has no rigid seat for a stopping point and allows the bellows to oscillate in perfect time with the tremolo is 55 shown in Figs. 4, 5 and 6. The bellows and intake box may be substantially as described above, except that the adjoining walls of the bellows and air box are provided with centrally aligned circular openings through which the sleeve 27 of the 60 valve mechanism extends. This sleeve may be formed of sheet metal, for example sheet iron, and it may be conveniently supported in proper position by a flange 28 that is secured to the sleeve and has apertures for receiving attaching 65 screws that hold the flange in tight engagement with a washer 29 on one of the walls through which the sleeve passes, which wall may be, as is shown in Fig. 4, that of the air box. Both ends of the sleeve 27 are open and the portion which 70 extends into the bellows is imperforate. The lower portion of the sleeve is provided with a plurality of parallel slots 30 which, in the aggregate, may occupy about one-half of the cylindrical surface of that portion of the sleeve which 75 is positioned within the air box. The sleeve

is of such length that the piston valve never passes beyond the sleeve during any normal operation of the system, i. e., the sleeve is substantially longer than the range of movement of the piston valve.

The valve proper may take the form of a wooden disk 31 which fits loosely within the sleeve and has a ring of soft, tough leather 31' secured to its lower surface and projecting so that it comes into approximate contact with the 10 sleeve. The slight clearance left between the disk and sleeve, possible because some leakage of air into the bellows is offset by the leakage through the organ, forms a noiseless and almost frictionless bearing of air around the piston and 15 allows it to ride perfectly free. The disk 31 is centrally apertured to fit upon the lower end of a rod 32 that is fixed to a board 33 carried by the bellows lid 8, and washers 34 are arranged between the clamp nuts 35 to provide air tight 20 joints.

Both of the illustrated forms of valves operate positively noiselessly with no appreciable friction, and admirably perform the function of an organ bellows valve. When the pedals (not 25 shown) or keys are actuated to open the valves of the organ pipes, air passes to them from the bellows, through the trunk 4, the lid 8 of the bellows sinks and the metal rod carries the valve 30 downwardly. When the valve opens, compressed air enters the bellows and tends to again close the valve as the air pressure acts upon the large area of the bellows lid 8. In addition to this function, which is performed more or less well by all organ bellows valves, both of the illustrated valves perform another very important function, that of freely oscillating in time with the beat of the tremolo. When a large amount of air is withdrawn suddenly by turning on the tremolo, the bellows lid 8 drops quickly, carrying 40 its valve with it. The compressed air rushes from the bellows well into the tremolo, through the open valve 15, forces up lid 18 of the tremolo bellows, which abruptly closes the felt-padded valve 15. The bellows lid 8 then swings upward, 45 carrying its valve. The air trapped in the bellows of the tremolo escapes through vent 17, weighted lid 18 falls, opening valve 15, through which compressed air again rushes from the organ bellows. This action is repeated rhythmically. 50 The bellows lid 8 often swings high enough to carry the valve slightly above its closing point, but as it is impossible for the valve to seat against a stop surface, the lid of the bellows can complete its upward swing without interruption, and 55 thus beat in perfect time with the tremolo.

It is to be understood that the embodiments of the invention shown and described are the preferred forms but that the invention contemplates such other modifications as fall within the scope 60 of the appended claims.

I claim:

1. In a pipe organ, the combination with a plurality of pipes, a bellows, a trunk connecting said pipes and bellows, and an air intake box 65 having an opening in the upper wall thereof, said bellows being seated on said intake box and having an opening aligned with said air intake box opening, of a valve controlling communication between said intake box and said bellows, and an 70 operating member for said valve connected to the upper rigid wall of said bellows, said valve being of the non-stop type.

2. A pipe organ as claimed in claim 1, wherein one of the aligned openings of said intake box and 75

bellows is of rectangular form, and said valve comprises a rectangular member pivotally supported in said rectangular opening.

3. A pipe organ as claimed in claim 1, wherein the opening in said air intake box is of rectangular form, and said valve is a rectangular block pivotally supported in the rectangular opening of said intake box.

4. In a pipe organ, the combination with a bellows having a floating top wall, and an air intake box below said bellows, said bellows and air intake box having aligned openings forming a passage between the same, of a valve in and of smaller size than said passage to leave a leakage opening entirely around said valve when the latter stands in closed position, and operating means connected between said valve and the floating top wall of said bellows.

5. In a pipe organ, the combination with a bellows having a floating lid, and an air box beneath said bellows, of a valve sleeve mounted on the bottom wall of said bellows and extending in opposite directions therefrom, the portion of the sleeve within the bellows being imperforate and the portion within the air box being apertured, a piston valve within said sleeve for controlling air flow through said apertures, and means rigidly connecting said piston valve to said bellows lid, said sleeve being unobstructed and open at both ends and of a length exceeding the range of movement of the piston valve.

6. In a pipe organ, the combination with an air box and a trunk leading to organ pipes, of a bellows connected between said air box and trunk, said bellows comprising a bottom and rigid side walls joined to a lid by a flexible wall section, an opening in said bottom wall, a sleeve extending through said opening, an exterior flange on said sleeve and seated on said bottom wall, said sleeve being imperforate above said bottom wall and apertured below the same, a piston valve within said sleeve, and means rigidly securing said piston valve to the bellows lid.

7. The invention as claimed in claim 6, wherein said valve comprises a disk and a flexible ring on said disk having a loose fit within said sleeve.

8. The invention as claimed in claim 6, wherein said valve comprises a disk and a flexible ring on said disk having a loose fit within said sleeve; and said securing means comprises a rod secured

to the bellows lid and means rigidly attaching said disk to said rod.

9. A pipe organ having an air control assembly of the type including a bellows having a floating lid, an air box beneath said bellows, and a valve actuated by said lid to control the flow of air from said air box into said bellows, characterized by the fact that said valve includes a sleeve open at both ends and extending into the air box and bellows respectively, and a piston valve in said sleeve and secured to said bellows lid.

10. A pipe organ comprising a plurality of pipes, and means for supplying air under pressure to said pipes; said means comprising a bellows having a floating lid, an air conduit beneath the bottom of said bellows, a valve sleeve mounted on the bottom wall of said bellows and extending in opposite directions therefrom, the portion of the sleeve within the bellows being imperforate and the portion within the conduit being apertured, a piston valve within said sleeve for controlling air flow through said apertures, and means connecting said piston valve to said bellows lid.

11. In a pipe organ, the combination with an air box and a trunk for supplying air to organ pipes, of a bellows between said air box and trunk, said bellows having opposite walls flexibly connected to form a chamber of variable size, an opening in one of said walls affording communication with said air box, a tubular sleeve extending through said opening, a sliding valve in said sleeve, said sleeve being open at both ends and having a perforate and an imperforate wall section located at opposite sides of said opening, and means connecting said valve to the other of said opposite walls.

12. A pipe organ comprising a plurality of pipes, means for supplying air under pressure to said pipes for sounding the same, and key-actuated means for controlling the flow of air to said pipes; said air supply means comprising a bellows having a lid flexibly connected to the bottom wall, an air conduit beneath the bottom wall, a trunk opening out of the bellows to pass air to the pipes, a sleeve extending through said bottom wall into the bellows, the portion of the sleeve at one side of the bottom wall being imperforate and that at the opposite side being apertured, and a sliding valve within said sleeve, and fixed to said lid.

GEORGE M. QUAVE.
